UNITED STATES PATENT OFFICE.

LOUIS D. SINGER, OF HARRODSBURG, KENTUCKY.

DESIGN FOR A WAX FLORAL WREATH.

56,631.

Specification for Design.

Patented Nov. 16, 1920.

Application filed June 28, 1920. Serial No. 392,160. Term of patent 7 years.

To all whom it may concern:

Be it known that I, LOUIS D. SINGER, a citizen of the United States, residing at Harrodsburg, in the county of Mercer and State of Kentucky, have invented a new, original, and ornamental Design for a Wax Floral Wreath, of which the following is a specification, reference being had to the accompanying drawing, forming part hereof.

The figure is a plan view of a wax floral wreath, showing my new design.

I claim:

The ornamental design for a wax floral wreath, as shown.

LOUIS D. SINGER.
